UNITED STATES PATENT OFFICE.

HERBERT ARNOLD RIMMER, OF ANNIESLAND, GLASGOW, SCOTLAND.

DEVICE FOR SUPPORTING CURTAINS.

Application filed August 8, 1925, Serial No. 48,981, and in Great Britain August 28, 1924.

This invention has reference to improvements in and relating to devices for supporting curtains and the like.

Curtains or screens, of the type known as casement or sash curtains, are fitted to window-sashes by being supported or mounted on rods or the like carried by hook-like supports or brackets fitted to the upper end of the sash. The end of the curtain is usually turned over and stitched to form a loop or casing which extends the breadth of the curtain and through which the rod is passed. There are two such curtains on each rod and each curtain, when drawn forward or extended, covers one half of the window.

The object of this invention is to provide the curtain rod or the like with improved devices adapted to facilitate the fitting of the curtain on the rod, the drawing forward or extension of the curtain and the drawing back or draping of the curtain evenly down the sides of the window.

According to this invention these improved devices consist of a rod or the like carried by suitable brackets and having two caps mounted thereon one at each end of same. Two springs are also mounted on the rod and are secured one to each cap while catch devices adapted to engage each other are secured to the adjacent ends of the springs. Preferably the said catch devices comprise flanges having tongues adapted to engage each other and provided on sleeves secured to the springs and mounted on the rod.

In order that others skilled in the art to which this invention relates may properly understand the same I have hereunto appended one sheet of explanatory drawings in which Figure 1 is a front elevation, shown broken for convenience of illustration, of a pair of sash or casement curtains, shown diagrammatically, mounted on a rod provided with springs according to this invention. Figure 2 is a plan view, partly in section, corresponding to Figure 1. Figures 3, 4 and 5, illustrate certain details which will be hereinafter referred to more particularly.

Referring to these drawings:—

In carrying this invention into effect or

practice a rod, tube or the like *a* is provided with two spiral springs *b*. The outer extremity of each spring *b* is secured into a cap or the like *c* which fits, it may be loosely, on to the end of the rod *a*. As illustrated by Figure 3, which comprises an elevation, a plan view and two end views of the cap *c* according to one construction, the end of the spring *b* may be screwed into the cap *c*. The inner end of the cap may be provided with an inwardly extending radial flange *c*¹ having a gap or opening *c*². The end of the spring would be passed through the gap into the cap with a screwing movement so that the flange *c*¹ acts as a screw thread which engages the coils of the spring. By turning or rotating the spring it is screwed into the cap. The outer end of the cap *c* is provided with an inwardly extending flange *c*³ which acts as a stop and limits the movement of the spring and also acts as a stop for the end of the rod within the spring. As illustrated by Figure 4 which comprises a sectional elevation and an end view of a slightly modified construction of cap *c*, the internal diameter of the cap fits tightly over the coils of the spring, the cap *c* consisting of a cylinder with one closed end. In this construction the spring is forced into the cap with a screwing movement in the reverse direction which contracts slightly the diameter of the spring so that fitted into the cap the spring resists any tendency to be pulled out and is held firmly.

The ends of the rod *a* are supported in suitable brackets which preferably consist of tubes *d* (which form sockets for the caps *c* on the ends of the rod *a*) adapted to screw on to projecting bosses *d*¹ carried by brackets or the like *d*² adapted to be secured to the window-sash by flanges *d*³.

It will be readily understood that by unscrewing one of the tubes *d* the rod *a* and springs *b* may be removed.

The inner or adjacent ends of the springs *b* are fitted with suitable catch devices which are adapted to engage each other.

As illustrated by Figure 5, which comprises an end view and a plan view of each of the catch devices, these catch devices consist of a sleeve *e* into which the end of the spring *b* is secured in a similar manner as already described for the caps *c*. The sleeves *e* are provided with flanges *e*¹ having projecting tongues *e*². The tongues of the

flanges of the sleeve at the end of the one spring are adapted to engage the tongues of the flange of the sleeve at the end of the other spring. If desired the flanges e^1 may be provided with projections e^3 to form a grip so as to facilitate the turning or twisting of the catch devices when engaging or disengaging same.

If desired the cap c may be dispensed with and the end of the spring may be anchored to the end of the rod a by having the end coil or coils of the spring of smaller diameter than the other coils so as to form a stop for the end of the rod.

15 When the catch devices are drawn forwards, towards each other, the springs are extended and are retained in that position by the tongues of the catch devices engaging each other.

20 When the springs are extending the curtains are drawn forwards by the loops f^1 of the curtains f resting upon the springs.

In fitting the curtains or screens f into position the rod a with the springs b is removed from the sockets or tubes d . Each end of the rod and therefore the spring on same is pushed through the loop or casing f^1 of the curtain f and then the rod and curtains are replaced on the supports d . Preferably the tongues e^2 of the catch devices engage each other with the springs extended while putting the curtains on the rod. When the catches are released from each other the springs return to their normal position carrying the curtains back or away from each other. The springs in moving back carry the curtains back evenly so that they are draped evenly down each side of the window. Since each spring is of the same length each curtain will be even and of the same size when draped; the springs putting the requisite "tucker" on the curtains and causing equal spacing. By springing back the curtains any loose dust which may have lodged on same is dislodged and since the curtains do not require to be pushed back by

hand the risk of soiling by handling is reduced to a minimum.

I claim:—

1. A device for supporting window sash 50 curtains comprising a rod; brackets adapted to support said rod; two caps mounted on said rod, one at each end of same; two pull springs mounted on said rod and secured one to each cap; and catch devices secured to the 55 adjacent ends of said springs to releasably hold the latter against contraction.

2. A device for supporting window sash curtains comprising a rod; brackets adapted to support said rod; two caps mounted on 60 said rod, one at each end of same; two pull springs mounted on said rod and secured one to each cap; a sleeve secured to the adjacent end of each spring; a flange on each sleeve; and tongues on each flange, the tongues of 65 the one flange member being adapted to engage the tongues of the other flange member to releasably hold the latter against contraction.

3. A device for supporting window sash 70 curtains comprising a rod; two spiral springs mounted on said rod; a cap screwed on to the outer end of each spring; a sleeve secured on to the inner and adjacent end of each spring; a radial flange on each sleeve; 75 interengageable tongues on each flange; and brackets adapted to support the ends of said rod and comprising sockets screwed to a plate having fixing means.

4. In a device of the character described, 80 a pair of supporting brackets, sockets carried by the brackets, a supporting rod having its ends seated in the sockets, a pair of coil pull springs on the rod having remote ends fixed against movement, said spring being adapted 85 for insertion in the usual horizontal loop of a curtain, sleeves fixed to the adjacent ends of the springs and slidable upon said rod, and interengageable catches on the sleeves to releasably hold the springs against 90 contraction.

HERBERT ARNOLD RIMMER.
